(57) **CLAIM**

The ornamental design for a navigation system with audio player, as shown and described.

DESCRIPTION

FIG. 1 is a perspective view of a navigation system with audio player;

FIG. 2 is a front view thereof;

FIG. 3 is a rear view thereof;

FIG. 4 is a left-side view thereof, the right-side view being a mirror image;

FIG. 5 is a top view thereof;

FIG. 6 is a bottom view thereof;

FIG. 7 is a perspective view of the navigation system with audio player, with the display component in an inserted position within the body of the player;

FIG. 8 is a front view thereof;

FIG. 9 is rear view thereof;

FIG. 10 is a left-side view thereof, the right-side view being a mirror image;

FIG. 11 is a top view thereof; and,

FIG. 12 is a bottom view thereof.
